(57) **CLAIM**

The ornamental design for a growing tower as shown and described.

DESCRIPTION

FIG. 1 is a front right perspective view of a growing tower showing my new design;

FIG. 2 is a rear view of the design shown in FIG. 1;

FIG. 3 is a left side view of the design shown in FIG. 1, with the right side view being a mirror image;

FIG. 4 is a top view of the design shown in FIG. 1; and,

FIG. 5 is a bottom view of the design shown in FIG. 1.

The evenly-spaced broken lines in the Figures illustrate portions of the growing tower that form no part of the claimed design.

1 Claim, 5 Drawing Sheets
